UNITED STATES PATENT OFFICE.

JOHN STEWART SIMPSON, OF INGOMAR, MISSISSIPPI.

CROSSTREE FOR TELEGRAPH-POLES.

1,215,883.

Specification of Letters Patent. Patented Feb. 13, 1917.

Application filed April 18, 1914. Serial No. 333,333.

To all whom it may concern:

Be it known that I, JOHN S. SIMPSON, a citizen of the United States, residing at Ingomar, in the county of Union and State of Mississippi, have invented certain new and useful Improvements in Crosstrees for Telegraph-Poles, of which the following is a specification.

This invention relates to cross trees for supporting telegraph and telephone line wires, and one of the principal objects of this invention is to provide means of simple construction for supporting electrical conductors or wires upon a telegraph pole, and to dispense entirely with the ordinary glass insulator.

Another object of the invention is to provide a cross tree or arm having a block or series of blocks supported thereon, said blocks having interposed insulators for the line wires, said insulators being entirely inclosed between the blocks and preferably formed of stone or similar inexpensive material.

The ordinary glass insulators on telegraph poles are constantly being broken by gunners in various parts of the country, and by persons throwing stones at the cross trees of the telegraph poles, and to keep in good order a great many of these telegraph poles and insulators is a source of considerable expense. It was to overcome the objections above referred to that this invention was devised, and to that end the insulators of this invention are entirely concealed, or lie flush with the outer surface of the cross tree, so that they cannot readily become injured by mischievous persons.

The objects and advantages above referred to may be attained by means of the construction illustrated in the accompanying drawings, in which:

Fig. 1 is a top plan view of a cross arm or cross tree made in accordance with this invention, and showing the electrical conductors broken away at opposite sides of said arm,

Fig. 2 is a side elevation of the same,

Fig. 3 is a sectional view taken through one of the blocks and the insulators connected thereto,

Fig. 4 is a face view of one of the insulators,

Fig. 5 is a top plan view of the same, and Fig. 6 is a side elevation of a telegraph

pole having a cross arm connected thereto, made in accordance with this invention.

Referring to the drawings, the numeral 1 designates a flat metal bar or support for a plurality of blocks 2 of wood or similar material, said blocks being utilized in pairs, one superposed upon the other and connected together by means of bolts 3 to which are fitted nuts for clamping said blocks together.

Seated in recesses in the inner faces of the blocks 2 are insulators 5, formed of stone or other inexpensive material, said insulators each having a roughened face 6 and projecting portions 7 having inclined sides 8. Extending entirely around the projecting portion 7 is a flat ledge 9. The insulators terminate flush with the surfaces of the blocks 2, and the line wires 10 are clamped between each pair of blocks 2 as shown. Any suitable number of blocks may be utilized, depending upon the number of line wires to be supported, and the bar 1 may be extended to support a large number of blocks if desired.

Disposed between the blocks 2 and supported upon the bar 1 is a bracing block 11 connected to the bar by means of bolts 12 and nuts 13, said block being provided with a perforation 14 for receiving a bolt 15. Secured to the under surface of bar 1 at its outer ends by the bolts 3, are the braces 16, their opposite ends connected to the telegraph pole 18 by means of the bolt 17.

From the foregoing it will be obvious that a cross tree made in accordance with this invention and provided with the interposed insulators seated in the blocks, serves to protect the insulators from injury either by accident or design, that the cost of insulation is comparatively slight, that the cost of construction is also low, and that the life of the insulators is extended and thus results in economy.

Various changes may be made in the details of construction without departing from the spirit and scope of the invention as defined in the claims.

What is claimed is:

1. A cross arm for electrical conductors comprising superposed blocks bolted on the upper surface of a bar, insulators carried by said blocks, said insulators lying flush with the sides of said supporting blocks, whereby said insulators are prevented from becoming easily broken, and projections formed

on the outer faces of said insulators at the central portion thereof whereby said insulators are prevented from moving laterally and longitudinally in said superposed blocks.

2. A cross arm for electrical conductors comprising superposed blocks bolted on the upper surface of a bar, the inner faces of said superposed blocks having centrally disposed transverse grooves extending from one longitudinal face to the other and having recesses intermediate the ends of the inner walls, substantially rectangular insulators having a centrally disposed projection

formed on the outer faces thereof, the longitudinal edges of said projection being beveled downwardly, and a ledge surrounding the projections, said inclined projections being adapted to be seated in said recess, and the ledge in said groove, as and for the purpose specified.

In testimony whereof I affix my signature in presence of two witnesses.

JOHN STEWART SIMPSON.
